V. R. HEFTLER

PROCESS OF ASSEMBLING FILTER STACK UNITS

Filed Dec. 30, 1927

UNITED STATES PATENT OFFICE.

VICTOR R. HEFTLER, OF DETROIT, MICHIGAN.

PROCESS OF ASSEMBLING FILTER-STACK UNITS.

Application filed December 30, 1927. Serial No. 243,602.

This invention relates to an improved method of assembling the component laminary elements of a filter construction such as is described and claimed in Letters 5 Patent No. 1,641,485, issued to me on September 6, 1927, which, however, made no effort to specify whether this particular phase of the device's manufacture should be effected manually or mechanically. The 10 positioning of each disc upon the correlating member may of course be effected manually, but this is at best a long and tedious operation, and the process herein described is designed to simplify and abbreviate the 15 work without impairment of the efficiency of the completed structure, it being understood, as clearly brought out in the patent referred to, that the essence of the filter stack is the substantially coaxial and non-rotatable as- 20 semblage of the two classes of filtering discs in such a way as to form the stack described; and let it be pointed out at the outset that while in that patent and herein the central or correlating stem was assumed 25 to be squared or at least rectangular, any non-circular cross section for the stem and for the correspondingly apertured center portions of the discs may be employed, with- 30 out departure from the fair spirit of my invention; for example, a hexagonal, octagonal, or elliptical contour could be adopted without change of function or results.

In the drawings:

Figure 1 is a plan view of two representative forms of filter disc which may be designated as A and B respectively, whose alternating arrangement about a correlating stem results in the building up of the filter element.

Figure 2 is a perspective of several of these discs positioned coaxially and sufficiently spacedly, so as to bring out their co-operating function when assembled in the filter stack as a whole.

Figure 3 is a perspective view of a ribbon of metal in which have been cut, in alternating relation along successive sections thereof, apertures corresponding in position to the intra-peripheral portions of a complete disc of each of the series, A and B.

Figure 4 is a plan view of such a ribbon.

Figure 5 is a fragmentary plan view suggesting a slight modification wherein a ribbon of double the ordinary width is provided, in order that transversely of each

unit of lengthwise extent two partially cut-away washer units may be simultaneously formed, one alongside of the other.

It will be observed that as to the particular form of disc herein illustrated, each 60 type, as A and B, is provided with a squared central aperture, as C, four equidistantly spaced holes, as D, and four intermediately placed cut-away portions, as E, but, that 65 relatively to the sides and corners of the squared hole C, these other two characteristic parts of the disc of series A and series B are placed on opposite sides of one another; for example, that whereas the lower right corner of the squared aperture 70 C in the disc A points radially outward substantially along the lower edge of one of the cut-away segments E, as brought out by the dotted line G, the corresponding lower right corner of the squared portion C of the 75 disc B similarly points outward along the dotted line H substantially following the top edge of one of the cut-away portions E.

It will be obvious from a study of the two 80 types of washer, A and B, shown side by side in Figure 1, that if one of them, as for example A, were turned through a half circle, with its edge nearest B as an axis, so as to be superimposed, face downward upon the latter, the two would, in this position be 85 of identical contour. Since, however, the process involves an entire abstinence from any overturning of either from their initial common plane as they are successively stamped out from the ribbon and fall successively in place in the stack, the two types 90 of washers do vary in the respects shown.

It is thus obvious that if an alternated 95 series of discs A and B are arranged about a squared stem passing through their similarly squared centers, the four open or cut-away peripheral portions E of each will lie in registry with unbroken peripheral portions as Q of the disc above and the disc below, thus constituting the inlets leading to 100 the longitudinal channels in the stack as a whole, formed by the alternated registry of the four holes D in each disc and of the inner ends of the four cut-away portions E of the adjoining discs. If however, some 105 means such as the squaring of the stem K and the corresponding shaping of the central aperture C in each disc were not resorted to, this arrangement would not be automatically effected when the discs are posi- 110

tioned on the correlating member, nor would it remain so even if they were thus positioned with great care at the outset. The obvious tediousness of the process of assembling discs of this character by hand, though of course it could be done, emphasizes the advantage of my improved process herein described.

It is of course old to stamp out selected portions or designs in each lengthwise unit of a metallic or other ribbonlike strip, and the first step of my process merely consists in thus preparing the strip M in the manner brought out in Figures 3 and 4, either by successive punching with alternated punches of variant cut or preferably by a single die cutting step, whose active points or edges result in a cutting of the groups of apertures designated as *a* and *b* in Figure 3. These, it will be noted, are identical, except for positioning of the holes D and apertures E relatively to the sides and corners of the square portion C. This still leaves the component material which is to result in the various discs sufficiently integrated with the web of the ribbon so that except for the forming of the holes it is unsevered therefrom. All that remains, however, to complete the contouring of each disc of either type A or type B is a further cutting operation by a round die, as L, whose line of operative activity is indicated by the dotted line J, which in Figures 4 and 5 is truly circular, whereas in perspective Figure 3 it is shown as elliptical.

To effect this, the partially prepared ribbon M is successively positioned aided if desired by the accurately spaced guide holes P near the lateral edges of the ribbon so that in turn each of these partly formed disc sections are axially coincident with the central axis of the squared stem K, or other correlating member which is placed slightly subjacent thereof. As each section of the ribbon is brought into this position, it is subjected to the action of a circular cutting die such as has just been described, and which I have indicated at L, which completes the severance in succession of those portions of the web of the ribbon which have formed the discs A and B from the remaining marginal portion thereof which may then be scrapped. These now severed disc sections are thus released by gravity-induced fall upon and over the squared stem K, and since they have been cut as regards their apertured portions in the alternating arrangement already mentioned, it is obvious that they will automatically fall thus upon and about the squared stem K thus effecting the assemblage of its component disc elements rapidly, accurately, and with a minimum of labor. In the ribbon illustrated in perspective in Figure 3, I have indicated at R the cut-out hole left in the ribbon M after the final stamping out of

each disc unit has been completed. In the broader form of ribbon illustrated in Figure 5 these holes P may conveniently be positioned along the middle line thereof.

I desire it to be understood that I do not confine the disclosure herein made to this specific form of disc illustrated, nor indeed to the somewhat variant forms illustrated in my Letters Patent above referred to, since the principle herein disclosed is equally adaptable to other forms, as well as to the preparation and positioning of discs for other uses than herein mentioned and of other material or contour.

What I claim is:

1. The process of assembling the alternated laminary elements of a filtering stack, which consists in first partially stamping out the diverse members in alternating relation from a ribbon, and thereafter successively subjecting each partially cut portion of the ribbon to the action of a cutting die positioned in coaxial relation over a receiving element.

2. The process of effecting the alternated positioning upon a non-circular stem of a series of laminary filtering discs of similar though variantly oriented interior perforation, consisting in first partially cutting out units of each type alternatingly from a ribbon and thereafter successively positioning each unit of the ribbon as thus cut in coaxial relation over a receiving means and subjecting it to the completing cutting action of a die of suitable contour, whereby each is blanked out from the remainder of the ribbon.

3. The process of building up about a stem a surrounding stack of laminary filtering elements in alternated peripheral registry, which consists in first perforating a ribbon with selected components of each type of disc in successive pairs, and thereafter successively positioning each section of the ribbon as thus prepared over the stem and completing the cutting operation by coaxially applied die action, whereby each unit is released in turn for descent to its desired position of relative orientation about the stem.

4. The process of forming and mounting about a stem a series of disc elements of similar contour though of alternated relative peripheral orientation, consisting in successively cutting out the interior portions of each disc lengthwise of a ribbon of the selected component material, and thereafter positioning each section of the ribbon as thus prepared in coaxial relation above the stem and successively liberating each unit from the surrounding web of the ribbon by coaxially applied die action, for descent about the stem in maintained relative peripheral arrangement.

5. The process of forming and positioning in alternating relation about a correlating stem a plurality of laminary filtering discs

- having corresponding though diversely positioned cut-away portions, consisting in first effecting the interior cutting required for each type of disc in alternating relation to the subjacently located stem, whereby each unit when freed from the web of the ribbon may fall about the stem in suitably oriented relation to the adjacent units. 45
- 5 along the ribbon of selected material, and thereafter successively positioning each unit of the ribbon as thus prepared in coaxial relation over the stem and subjecting it to further cutting operation along the line of 10 the intended periphery of each disc by a coaxially moving die member, whereby each disc unit is in turn released from the web of the ribbon for descent to its intended position about the stem.
- 15 6. The process of forming and positioning about a stem the component alternated discs of a filtering stack, which consists in first subjecting successive sections of a ribbon of selected material to alternatingly variant 20 cutting operations whereby the intra-peripheral apertures characteristic of each type of disc are made in desired relative position, and thereafter successively positioning each section of the ribbon as thus prepared in coaxial relation over the stem and effecting 25 the severance of each from the web of the ribbon by further appropriate cutting operation and allowing the then released and formed discs to fall into position about the 30 stem.
7. The process of producing filtering discs of variantly arranged intra-peripheral contour and of arranging them in desired alternation and relative orientation upon a cor- 35 relating stem, which consists in first cutting out partial outlines of each characteristic type in successive alternation along a ribbon of suitable material, and thereafter completing the severance of each unit from the web 40 of the material in similar sequence as each is successively positioned in coaxial relation
8. The process of assembling laminary units of alternatingly diverse peripheral orientation in superimposed relation, consisting in partially blanking the same from parent stock and subsequently completing the severance thereof in position of operative alignment over a receiving element, and delivering them to the receiving element. 50
9. The process of assembling in coaxial relation a plurality of laminary units which are peripherally similar though of alternatingly variant orientation, consisting in effecting their partial severance from parent stock and then successively completing the severance of the members of each class of 60 units in alternated relation over a receiving element whose operative engagement with each then severed unit effects the maintenance of their desired alternation. 55
10. The process of producing and positioning in alternated coaxial relation a series of laminary elements of similar though diversely oriented contour, consisting in first effecting the partial severance of the elements of each class from parent stock and 65 thereafter alternatingly presenting such partly severed elements to the final severing action of an operating member at the moment that each in succession is located operatively adjacent a receiving element whose 70 action thereupon results in the maintenance of the desired alternation of the several elements. 75

In testimony whereof I sign this specification.

VICTOR R. HEFTLER.
